TEXTILE SPOOL

Rawson Atwood, Garden City, N. Y., assignor to
Decorated Metal Manufacturing Company,
Inc., Brooklyn, N. Y., a corporation of New York

Application June 2, 1943, Serial No. 489,320

8 Claims. (Cl. 242—120)

This invention relates to improvements in textile spools and more particularly in winding tubes or pirns.

It is an object of the invention to provide an improved drive end construction for a flangeless pirn or winding tube.

A further object of the invention is to provide an improved drive end construction in conjunction with a tubular pirn or winding tube having a relatively thin wall.

A still further object of the invention is to provide an improved drive end construction in conjunction with suitable reinforcing structure for the tube barrel.

Another object of the invention is to provide an improved winding end construction for such a tube.

With the foregoing objects and others which will appear in the following full description in mind, the invention consists in the combinations and arrangements of parts and details of construction which will now first be fully described in connection with the accompanying drawing and then more particularly pointed out in the appended claims.

In the drawing:

Figure 1 is a central longitudinal section of a winding tube embodying the invention in preferred form and showing the parts in an intermediate stage of assembly;

Figure 2 is a side view of a completed winding tube, with parts progressively broken away to show the interior structure at the ends in central longitudinal section;

Figure 3 is a top view of the tube of Figure 2;

Figures 4 and 5 are transverse sections taken respectively on the lines 4—4 and 5—5 of Figure 2;

Figure 6 is a lower end view of the tube of Figure 2;

Figure 7 is a central longitudinal section of the lower part of the tube of Figure 2 and is taken on the line 7—7 of Figure 2; and

Figure 8 is a view showing a modified upper or winding end construction.

Referring now to Figures 1 and 2, the winding tube comprises the outer barrel 1, preferably of pasteboard, within which is a reinforcement assembly including an outer split metal tube 2 and an inner split metal tube 3. These metal tubes are preferably arranged with the splits facing oppositely so as to preserve dynamic balance. The tubes 2 and 3 are forced outwardly against the inner surface of the barrel 1 by the cup-shaped brace members 4 and spindle bear-

ing members 5. The members 4 and 5 are driven into the inner tube 3 so as to expand the tubes 2 and 3 against the inner surface of the pasteboard outer barrel 1. As will be observed, the structure just described is generally similar to that disclosed in my applications, Serial Nos. 411,001 and 411,002 filed September 16, 1941, and the present invention constitutes in certain aspects an improvement thereon.

10 The cup-shaped members 4 have central openings 6 to permit passage of a spindle and these openings are preferably of sufficiently large diameter as to not engage the spindle. Each bearing member 5 comprises a cylindrical skirt or longitudinal flange 7 which fits within the inner tube 3 and is contracted at 8 to form a tubular bearing adapted to receive and engage a spindle.

The parts thus far described are shown in assembled condition in Figure 1 and the assembly

20 is completed by adding to the sub-assembly there shown the drive end 9 and winding end member 10. The drive end member 9 comprises a generally cup-shaped or ferrule shaped sheet metal structure having a cylindrical flange wall 11 and being formed to seat upon a whorl and engage the lugs of the same. For this purpose a key-shaped opening is provided in the bottom of the member 9 and this extends upwardly into the flange wall 11 as shown in Figures 1 and 7. The central

25 portion of the opening is preferably enlarged sufficiently so that it does not engage the spindle. The edges of the opening are formed with flanges 12 which are turned axially inward, and with side flanges 13 and 14, which are turned transversely inward. These flanges serve as bearing surfaces for engaging the whorl and also to strengthen and finish off the edges of the opening. The outer pasteboard barrel 1 is notched as at 15 (Figure 1) to accommodate the flanges

30 13, 14, so that the member 9 may be driven onto the drive end of the winding tube. As will be seen from Figures 1, 2 and 3, the reinforcement tubes 2 and 3 are spaced from the drive end of the barrel 1 by a distance substantially equal to the depth of the slot of the drive end member 9, so that the member 9 can seat against the end of the tube 1 and the flanges 14 be pressed down substantially flush against the bottoms of the notches 15. The drive end assembly is completed by rolling the upper edge 16 of the flange wall 11 into the barrel 1 so as to hold the member 9 securely thereon and to provide a joint which will not trap the thread or fiber to be wound upon the tube. A bearing member 5 is

35 preferably located adjacent this upper edge 16

40 45 50 55

so as to back up the barrel 1 and tubes 2 and 3 and thus provide a solid construction.

The upper ends of the tubes 2 and 3 preferably stop short of the upper end of the barrel 1 and the top assembly may be completed by inserting the winding end member or end cap 10 and turning over and rolling in the flange 11 thereof as indicated in Figures 1, 2 and 3. The advantages of this construction, which is made possible by eliminating any spindle bearing function of the winding end member, are apparent. Winding end member 10 comprises a cylindrical portion 18 which engages the pasteboard tube 1 and a further cylindrical portion 19 formed with nibs or projections 20 and which may receive an identification disk to be held down by the nibs. Member 10 preferably has an opening 21 to provide for access to the interior of the winding tube at the upper end when necessary, and leaving an annular flange for supporting the identification disk below the projections 20.

It is desirable to employ flangeless winding tubes with spindles designed also for flanged tubes. In the case of a tube having a lower flange the thread or fiber will be wound thereon so as to form a mass which extends out along the flange at its lower end but tapers toward the flangeless upper end. However, when the fiber or thread is wound upon a flangeless tube, it must be wound with a taper at both ends, so that it is desirable to make the tube somewhat longer than a flanged tube, and also to wind the thread or fiber as close to the lower end as possible. For this reason the upper bearing member 5 should be positioned within the tube at a low enough point to engage a spindle which will normally terminate considerably short of the upper end of the winding tube. This permits upward extension of the winding tube to the desired amount. At the lower end, the skirt 11 need extend above the flange 14 or lug-engaging slot only sufficiently to furnish a secure fastening. In this way the maximum depth of winding upon the tube is provided for.

As will be noted the drive end member 9 seats longitudinally against the pasteboard barrel 1 and is positioned transversely with reference thereto. Inasmuch as this member does not engage the spindle but merely seats upon the whorl and engages its lugs, a sufficiently accurate positioning of the member is obtained. It will be noted that, while a pasteboard tube is relatively unsatisfactory as a support for holding a drive end member in accurately concentric position, it is adequate for holding the member in position axially and the tube is held in concentric position by the bearing members 5 which are positioned with reference to the split metal reinforcement assembly.

Figure 8 illustrates a relatively inexpensive winding end construction in which the winding end member 10 is omitted and the outer barrel 1 is merely turned over adjacent this end so as to form a rounded nose or bearing surface.

The constructions illustrated are flangeless 65 pins or winding tubes intended to be supported

and driven at one end and to be left free at the other. Certain features of the invention are, however, applicable also to winding tubes which are driven or supported at both ends and also to pins having a single flange at the drive end.

5. What is claimed is:

10. 1. In a flangeless textile winding tube and in combination, a pasteboard outer barrel, a tubular reinforcement within said barrel, a spindle bearing 15 within said reinforcement, and a ferrule-shaped drive end member comprising a bottom seating against the end of the said barrel and a flange wall fitting over the end of said barrel and pressed into the same opposite said reinforcement member to fasten the drive end member to the barrel, the said drive end member having a drive slot formed therein.

20. 2. In a flangeless textile winding tube and in combination, a pasteboard barrel having notches 25 at its drive end to accommodate the lugs of a whorl, a tubular reinforcement within said barrel and terminating short of said notches, and a ferrule-shaped drive end member comprising a bottom seating against the end of said barrel and a flange wall fitting over the end of said barrel and pressed into the same opposite said reinforcement to fasten the drive end member to the barrel, the said drive end member having a drive slot formed in the bottom and flange wall thereof in alignment with the said notches.

30. 3. A winding tube according to claim 2 in which the material of the said drive end member is formed into inwardly extending flanges surrounding said drive slot.

35. 4. A winding tube according to claim 2, comprising also a spindle bearing with said reinforcement.

40. 5. A winding tube according to claim 2, comprising also a spindle bearing within said reinforcement and in which the said drive slot includes an enlarged central portion of greater diameter than said spindle bearing to provide clearance around a spindle engaging said bearing.

45. 6. In a pin, a tubular pasteboard barrel, a tubular reinforcement within said barrel, a drive end member for said barrel, spindle bearings within said reinforcement, the said barrel extending beyond said reinforcement at its winding end, and a winding end cap attached to said barrel beyond said reinforcement.

50. 7. A pin according to claim 6, in which the said end cap comprises a cylindrical portion fitting within the said barrel, an annular flange 55 below said cylindrical portion, and inward projections above said flange for holding an identification disk.

55. 8. In a pin or the like, a tubular pasteboard barrel, a tubular reinforcement within said barrel, a drive end member for said barrel, and spindle bearings within said reinforcement, the said barrel extending beyond said reinforcement at its winding end and being contracted at its edge to form a rounded bearing surface.

RAWSON ATWOOD.
